J. C. THOMAS.
PRINTING AND SERVING MACHINE,
APPLICATION FILED FEB. 15, 1917.

1,256,078.

Patented Feb. 12, 1918.

UNITED STATES PATENT OFFICE.

JOHN C. THOMAS, OF DETROIT, MICHIGAN, ASSIGNOR TO DETROIT PRINTING AND SERVING MACHINE COMPANY, OF DETROIT, MICHIGAN, A CORPORATION OF SOUTH DAKOTA.

PRINTING AND SERVING MACHINE.

1,256,078.

Specification of Letters Patent. Patented Feb. 12, 1918.

Application filed February 15, 1917. Serial No. 148,796.

To all whom it may concern:

Be it known that I, JOHN C. THOMAS, birth name CLAYTON E. WYRICK, a citizen of the United States, residing at Detroit, 5 county of Wayne, State of Michigan, have invented a certain new and useful Improvement in Printing and Serving Machines, and declare the following to be a full, clear, and exact description of the same, such as will 10 enable others skilled in the art to which it pertains to make and use the same, reference being had to the accompanying drawings, which form a part of this specification.

This invention relates to machines for 15 printing and serving paper from rolls, and its object is a machine for printing the paper as it is used from the roll. Another object of the invention is a machine for printing and serving paper from rolls in which an 20 original and copies are made at the same time. These and other objects and the several novel features of the invention in its preferred form are hereinafter more fully described and claimed and shown in the accompanying drawings in which— 25

Figure 1 is a view of the device, one of the side members being removed therefrom.

Fig. 2 is a view of a portion of the top of the machine showing the hand rest and 30 means for tearing the sales slips.

Fig. 3 is a view of the means for holding the carbon paper between the paper strips.

Similar characters refer to similar parts throughout the drawing and specification.

35 The device consists of the framework 1 and the end plate 2 which at the top provides a hand rest 3 for the operator. A plate 33 is also provided which forms a rest for the paper so that it may be written 40 on. A roller 4 is mounted in the main part of the frame on the shaft 5 which is adapted to rotate in the frame 1 and may be provided with a crank with which to rotate the roll 4 or the paper strips may be moved by 45 pulling forward on the ends of the strips 25 and 26. A roll 6 is also provided having a shaft engaging in bearings on the frame 1. As will be noted more particularly in Fig. 1, as the roll 4 is rotated the paper 50 from the roll 6 is unwound running over the idling pulleys 7, 8 and 9 and thence to the roll 4. At about the center of the frame 1 a paper supply roll 10 is provided, the paper therefrom being adapted to roll 55 over the pulleys 11 and 8. At the end of the frame 1 another supply roll 12 is pro-

vided from which the paper passes over the rolls 13, 14, 15, 16 and 17 and over the roll 8 onto the plate 33. Between the rollers 11 and 13 a type roller 18 is mounted, being provided with spaces to receive type on the outer periphery thereof, the type being set up in the form desired to be printed on the paper strips. To ink the type on the roll 18 a felt roller 19 is provided in contact with the roller 18, the felt roller being saturated with ink so that upon rotation of the roller 18, the type on the surface thereof is inked. The rollers 11 and 13 are preferably made of rubber or some material that will hold the paper from the rolls 10 and 12 tightly in contact with the type upon passage of paper thereby. A bevel edged metal strip 20 is provided at one end of the frame across which the paper is drawn when it is necessary to tear it. As is shown more particularly in Fig. 3, two shafts 21 and 22 are mounted in the frame, the shafts being stationary. Sheets of carbon paper are secured about these shafts 25 by the clips 23 and 24, the position of the shafts being shown more particularly in Fig. 1, the shafts and carbon paper thereon being interposed between the strips of paper, the carbon paper being stationary the strips 80 of paper can be moved without moving the carbon paper.

To operate the device the operator writes on the paper which appears at 28. By writing on the top paper strip 25 a copy is produced through the carbon sheet to both paper strips 26 and 27. When the writing has been finished the operator can either pull forward on the strips 25 and 26 and tear them off across the metal strip 20 or by 90 securing a crank to the shaft 5, he may turn the crank which would also move the paper strips forward to position to be torn. As will be noted more particularly in Fig. 1, as the sheets 25 and 26 are moved forward 95 they are printed adjacent the roller 18 by the type which is mounted therein. This type is set up in any form the operator desires, the rolls 10 and 12 being plain paper and as they pass between the rollers 11 and 18 and 13 and 18 respectively they are 100 printed, the roller 19 inking the type on each rotation of the roller 18. Thus it will be seen that the paper is printed just before being used, the strips 25 and 26 being 105 printed before appearing in the opening 28. The rollers 4 and 6 are also plain paper and

as before explained by writing on the slip 25 a carbon copy is made on the strips 26 and 27. The bevel edged metal strip 20 is positioned near the end of the sheet so that 5 when the strips are moved forward they may be torn off at the bottom of each printed portion. As before explained the carbon paper is held in position by the shafts 21 and 22 and clips 23 and 24 so 10 that the carbon paper is always beneath the opening 28, the paper strips 25, 26 and 27 being adapted to move over and between the carbon sheets.

The novel features of this invention exist 15 more particularly in the printing of the paper and serving thereof almost immediately after printing. Another novel feature of the invention exists in printing several strips of paper from the same type 20 simultaneously.

From the foregoing description it becomes evident that the device while of a simple nature is very efficient in operation and of comparatively cheap construction.

25 Having thus briefly described my invention, its utility and mode of operation, what I claim and desire to secure by Letters Patent of the United States is—

1. In a printing and serving machine, a 30 suitable framework, a pair of paper rolls rotatably mounted therein, a rotatable type roller or form, means for holding the strip from each paper roll in engagement with the face of the type roll upon opposite sides 35 thereof whereby the strips are printed substantially simultaneously on adjacent sides upon withdrawal of the strips from the rolls, a raceway through which the paper strips are passed, means for reversing one 40 of the strips prior to its introduction into the raceway whereby the printed surfaces of the strips are both positioned with printed side up in the raceway, a stationary carbon sheet positioned between the strips in 45 the raceway, and means for severing portions of the strips from the body thereof.

2. In a printing and serving machine, a framework, a plurality of paper rolls rotatably mounted therein, means for printing 50 the paper from two of the rolls on the adjacent sides thereof, a roll of blank paper, a raceway through which the printed and blank paper passes, carbon sheets stationarily positioned between the respective strips 55 a takeup roller for the blank paper, and means whereby the printed sheets may be severed from the respective strips.

3. In a printing and serving machine, a plurality of paper rolls rotatably mounted 60 therein, means for printing the paper from two of the rolls on adjacent sides thereof, means for serving the printed strips printed side up with the printing on the said strips

in registration, a roll of blank paper, a raceway through which the printed and blank 65 paper passes, carbon sheets stationarily positioned between the respective strips, a takeup roller for the blank paper, and means whereby the printed sheets may be severed from the respective strips. 70

4. In a printing and serving machine, a framework, a plurality of paper rolls rotatably mounted therein, a type roller, means for holding the strips from each paper roll in engagement with the face of the type roll 75 whereby the strips are printed upon withdrawal from the rolls, means for serving the printed strips printed side up with the printing on the said strips in registration, a roll of blank paper, a raceway through 80 which the printed and blank paper passes, carbon sheets stationarily positioned between the respective strips, a takeup roller for the blank paper, and means whereby the printed sheets may be severed from the 85 respective strips.

5. In a printing and serving machine, a framework, a plurality of paper rolls rotatably mounted therein, means for printing the paper from two of the rolls on the adjacent sides thereof, a raceway into which the printed paper is introduced printed side up with the printing thereon in registration, carbon sheets stationarily positioned between the printed strips, and means whereby 90 the printed sheets may be separated from the respective strips. 95

6. In apparatus of the character described, a framework, a pair of paper rolls rotatably mounted therein, a printing roller 100 adapted to print on adjacent faces of the strips as drawn from the two rolls, means for delivering the printed strips printed side up with the printing thereon in registration, a carbon sheet stationarily positioned between the printed strips, and means 105 whereby printed portions in registration may be consecutively severed from the strips.

7. In apparatus of the character described, a framework, a plurality of paper rolls rotatably mounted therein, a single printing roller adapted to print on one side of each strip as drawn from the rolls, means for delivering the printed strips 110 printed side up with the printing thereon in registration, carbon sheets stationarily positioned between the respective printed strips, and means whereby printed portions 115 in registration may be simultaneously severed from the several strips in consecutive order longitudinally of the strips. 120

In testimony whereof, I sign this specification.

JOHN C. THOMAS.
